LATCH FOR ROLLING METAL GATES

Vincent Greco, 195 Huntington Ave.,
Bronx, N.Y. 10465

Filed Feb. 1, 1974, Ser. No. 439,071

Term of patent 14 years

Int. Cl. D8—07

U.S. Cl. D8—127

FIG.1

FIG.2

FIG.3

FIG. 1 is a perspective view showing my new design of a latch for rolling metal gates, the pin partly broken away to show indeterminate length.

FIG. 2 is a perspective view of the pin-carrying member shown in FIG. 1.

FIG. 3 is a side elevation view of the anchor pin.

I claim:

The ornamental design for a latch for rolling metal gates, as shown and described.
